UNITED STATES PATENT OFFICE

REIMUND ULLRICH, OF BERLIN, GERMANY

VALVE FOR CONTROLLING GASES AND LIQUIDS

Application filed February 29, 1928, Serial No. 258,052, and in Germany November 2, 1925.

The invention consists in a valve for gases and liquids which is particularly adapted for use with gas meters, and in which the outlet is closed by squeezing or compressing a flexible member made in the form of a collapsible envelope or member of material such as thin leather or rubber.

The invention differs from known devices of this kind in that the flexible member is connected with a tilting operating valve plate which, in one inclined position, opens a passage in one direction and closes it in the other direction, while in the other inclined position the connection is closed in the first and opened in the other direction.

It is preferable to connect several valve plates in pairs with the flexible member and to mount them so that several passages can be controlled simultaneously but in different directions.

This invention, which is particularly adapted as a controlling device for dry gas meters, possesses many advantages over the plane or tubular slide valves and spherical or disc valves formerly used for this purpose due to its simple construction and easy manipulation, and since the surfaces to be sealed are, for the same opening, only half as long as in known closing devices, they can be maintained secure from leakage for a longer time.

The accompanying drawings show examples of constructions according to the invention.

Fig. 1 is a vertical section of a single valve in the open position, and Fig. 2 in the closed position.

Fig. 3 is a plan of the side of opening with the valve open, and Fig. 4 is an elevation showing the valve closed.

Fig. 5 is a vertical section of the valve applied to a dry gas meter.

Fig. 6 is a section taken on line 6—6 of Fig. 2.

In Figs. 1 to 4, and 6 a flexible member or tube *s* is shown composed of some flexible or elastic material, such as rubber or leather. This member or tube is flatly compressed and its lower half *h* is fastened on a base plate or partition *g*, the upper half *h'* of the envelope being connected to and movable with

the valve plate *p* which is preferably a channel plate provided with downwardly inclined edges *k*, *k'*, the edges extending transversely over and externally of the whole breadth of the flatly compressed envelope *s*. In the inner side of the envelope openings *t* are cut to correspond with openings *o*, or, as shown in Fig. 5, to openings *d*, *d'*, *d*² and *d*³. A rod *l* linked to the plate *p* can be pushed or pulled so as to rock or lift one side of the valve plate *p* at a time, that is, the valve is opened and alternately tilted to either side, so that in one position of the plate *p* the passage *o* is opened to one side and closed to the other side, or vice versa, so that a passage is opened from the space above the base plate *g* through the passage *o* to the space below.

Each end of the envelope *s* is closed and secured to the partition *g* by a plate *u* extending transversely of the upper ply of the envelope; and a ring *q* clamped against the upper side of the lower ply of the envelope around the hole *t* in said ply secures said lower ply to the partition *g*. The upper ply of the envelope is secured to the under side of the plate *p* and a portion of said upper ply is folded around one end of said plate and pinched between the upper side of said plate and a plate *u*.

The valve system, when used as a controlling device for a dry gas meter, (Fig. 5), has a continuous flexible envelope *s* with valve plates *p*, *p'*, *p*², *p*³ which are coupled in pairs by connecting rods *v* or *v'* and are preferably under the action of springs *f*, *f'*.

Measuring chambers *r*, *r*₁, *r*₂, and *r*₃ are formed in the space below the partition *g* by a vertical partition and vertical flexible diaphragms *m* and *m*₁, one of said diaphragms being located on each side of said vertical partition. Openings *t* in the lower ply of the flexible tube or envelope *s* register with openings *d*, *d*₁, *d*₂, and *d*₃ formed in the partition *g* and leading, respectively, to said measuring chambers. Further openings *t'* in the lower ply of the envelope *s* register, respectively, with outlet passages *a* and *a*₁ in the partition *g*. The outlet passage *a* is immediately above the upper end of the diaphragm *m* and is therefore common to the measuring

chambers r and r_1 ; and the outlet passage a_1 is immediately above the upper end of the diaphragm m_1 and is therefore common to the measuring chambers r_2 and r_3 .

5 The tilting valve plates p, p_1 , are coupled by a connecting rod v , and the tilting valve plates p_2, p_3 are coupled by a connecting rod v_1 , the connecting rods v and v_1 being actuated, respectively, by springs f and f_1 .

10 Links l or l' of each valve pair are operated by two crank pins z and z' which are relatively displaced at about 90° , and the shafts w of the pins are driven in any known manner from the diaphragms m and m^1 of the 15 gas meter.

15 In the position shown by Fig. 5, the left-hand valves are closed, the right-hand valves being tilted to the right side and opened. As indicated by the arrows, the gas enters the 20 measuring chamber r_2 from the space above the partition g through the passage d_2 and presses the diaphragm m_1 into the measuring chamber r_3 , so that the gas filling this chamber is driven out through the passages d_3 and 25 a_1 connected by the attached part of the envelope s . When the diaphragm m_1 is at the end of its stroke, it moves, through suitable mechanism, the shaft w about a quarter of a turn in the direction indicated by the arrows, 30 moving the pins z and z_1 , and thus actuating the rod v_1 by means of the link l_1 to close the passages d_2 and d_3 , and also actuating the rod v by means of the link l to tilt the left-hand valve plates p and p_1 to the right, so that the 35 measuring chamber r is connected with the inlet room above the base g through the passage d , while the chamber r_1 communicates with the gas outlet through the passages d_1 and a .

40 The gas entering fills the empty chamber r and, by moving the diaphragm m , presses out the gas from the replenished chamber r_1 . When the diaphragm m has reached the end of its stroke, the shaft w is moved again, the 45 valves p and p_1 are closed, the valves p_2 and p_3 are tilted to the left to cause communication of the replenished chamber r_2 through the passages d_2 and a_1 with the gas outlet, and also communication of the empty 50 chamber r_3 through the passage d_3 with the inlet room above the base g . The diaphragm m_1 moving to the left, again moves the shaft w to cause the emptying of the chamber r through the passages d and a and the 55 replenishing of the chamber r_1 through the hole d_1 . The diaphragm m is pressed to the left, the shaft w is moved about a quarter of a turn, and thus all parts of the system have again reached the position illustrated in Fig. 5.

60 The right- and left-hand pairs of valves close and open alternately to either side, causing the filling and emptying of one measuring chamber after another and oscillating the shaft w .

65 In dry gas meters with only one diaphragm,

the present valve system may be employed as a controlling device.

I claim:

1. The combination with a partition having a port therethrough, of a valve mechanism therefor including an elongated open ended flexible member having an upper and lower layer resting upon the partition and having an opening formed through the lower layer thereof registering with said port, a plate attached to the upper layer of the member above the port and opening, and means for rocking said plate to cause the port to be covered or be opened from either side. 70

10 2. The combination with a partition having a port therethrough, of a valve mechanism including an elongated open ended flexible member having upper and lower layers lying in position upon said partition and having an opening through the lower layer thereof 75 aligned with said port, means to secure the member to the partition about said port, a channel plate attached exteriorly to the upper layer and adjacent the port and disposed to normally compress the member and close 80 the port by impinging the layers of the member together upon opposite sides of the port, and means for rocking the plate upon its respective edges to separate the layers at either 85 side of the port. 90

95 3. The combination with a gas meter having two superposed chambers, two diaphragms and a partition in the lower chamber dividing the same into two pairs of compartments, a partition between the chambers being provided with two sets of three ports each, one port for each compartment and one port at the juncture of each pair of compartments, of a valve mechanism for controlling 100 said ports including an elongated open ended flexible member having upper and lower layers attached at its ends to the last-named partition and having ports through the lower layer thereof registering with the ports in the last-named partition, means for holding 105 the upper layer of said flexible member spaced from the ports at the juncture of each pair of compartments, four channel plates attached to said upper layer, one adjacent each of the remaining ports and normally forming 110 with the upper layer a closure for its associated port, and means connected to said plates for operating the same in pairs to 115 cause the plates to rock and control the various ports. 120

125 4. The combination with a gas meter having two superposed chambers, two diaphragms and a partition in the lower chamber dividing the same into two pairs of compartments, a partition between the chambers provided with two sets of three ports each, one port for each compartment and one port at the juncture of each pair of compartments, of a valve mechanism for controlling said ports including an elongated open ended flex- 130

ible member having an upper and lower layer attached at its ends to the last-named partition and having ports through its lower layer registering with the ports in the last-named partition, means for holding the upper layer of said flexible member spaced from the ports at the juncture of each pair of compartments, four channel plates attached to said upper layer one adjacent each of the remaining ports and normally forming with the upper layer a closure for said ports, two arms hingedly connected, respectively, to the pairs of plates, and means for rocking the two arms in unison.

In testimony whereof I have hereunto set
15 my hand.

REIMUND ULLRICH.
